UNITED STATES PATENT OFFICE.

JACOB GARLINER, OF ROCHESTER, NEW YORK.

DESIGN FOR A CUFF BUTTON.

Application filed March 25, 1922. Serial No. 1,388. Term of patent 14 years.

To all whom it may concern:

Be it known that I, JACOB GARLINER, a citizen of the United States, residing at Rochester, in the county of Monroe and State of New York, have invented a new, original, and ornamental Design for a Cuff Button, of which the following is a specification, reference being had to the accompanying drawing, forming part thereof.

In the drawing:

Fig. 1 is a side view of a cuff button, showing my new design;

Fig. 2 is a view of the opposite side of my new design; and

Fig. 3 is an end view of my new design.

I claim:

The ornamental design for a cuff button, as shown.

JACOB GARLINER.
